UNITED STATES PATENT OFFICE.

ROBERT J. KRAUSE, OF DEHESA, CALIFORNIA.

CONTAINER AND SEALING-RING THEREFOR.

1,312,913.

Specification of Letters Patent. Patented Aug. 12, 1919.

Application filed November 12, 1915, Serial No. 61,069. Renewed March 11, 1918. Serial No. 221,867.

To all whom it may concern:

Be it known that I, ROBERT J. KRAUSE, a citizen of the United States, residing at Dehesa, in the county of San Diego and 5 State of California, have invented certain new and useful Improvements in Containers and Sealing-Rings Therefor, of which the following is a specification, reference being had therein to the accompanying 10 drawing.

The invention relates especially to a container comprising a jar and a cover therefor preferably of novel construction as herein-after described, and a sealing ring between 15 the jar and the cover and so constructed that it can be readily disintegrated or destroyed mechanically while the cover is in place. The invention can be embodied in any of a number of ways, some of which are illustrated in the accompanying drawing. But 20 it will be understood that this drawing is intended for illustrative purposes only and not for the purpose of defining the invention, reference being had for that purpose 25 to the claims appended to the specification.

Of the drawings,

Figure 1 is a vertical sectional view through a container embodying the invention.

30 Fig. 2 is a side view of the sealing ring. Fig. 3 is a view similar to Fig. 1 but illustrating another embodiment of the invention.

Fig. 4 is a plan view of the sealing ring 35 shown in Fig. 3.

Fig. 5 is a view similar to Figs. 1 and 3 but illustrating another embodiment of the invention.

Fig. 6 shows still another embodiment of 40 the invention, the sealing ring in this construction being similar to that shown in Fig. 4.

Fig. 7 is an enlarged plan view of another form of sealing ring.

45 Fig. 8 is an enlarged sectional view taken along the line 8—8 of Fig. 7.

Fig. 9 is an enlarged fragmentary plan view of still another form of sealing ring.

Fig. 10 is an enlarged sectional view taken 50 along the line 10—10 of Fig. 9.

Fig. 11 is an enlarged fragmentary plan view of still another form of ring.

Referring to the drawings, especially Figs. 1 and 2, 1 represents a jar, preferably of 55 glass, and adapted to contain any desired product, particularly a food product, such,

for instance, as canned fruit. The lower part of the jar can be constructed in any usual or preferred way. In the preferred embodiment of the invention the upper part 60 of the jar is provided with a conical surface at 2, preferably on the exterior. 3 represents the cover of the jar which is also preferably formed of glass. The cover is provided with a conical surface 4 parallel 65 to the conical surface 2, the surface 4 being on the interior of the cover when the surface 2 is on the exterior of the jar.

A sealing ring 5 is interposed between the 70 conical surfaces 2 and 4 of the jar and cover and is shaped to fit them. Its body part is formed of any suitable plastic substance. Preferably the body part of the ring is formed of rubber or some equivalent there-of or substitute therefor, but for some classes 75 of work the body part of the ring can be formed of paraffin or a similar compound.

Embedded in the body of the ring is a suitable tension means which can be pulled out progressively to cause the disintegration 80 and destruction of the ring without removing the cover from the jar. This tension means can be of any of a number of forms, but the form which I prefer and which I have shown in Figs. 1 and 2 comprises a 85 flexible tension device such as a wire or cord arranged spirally within the body of the ring. Preferably when the body of the ring is formed of rubber there is initially constructed a strip of unvulcanized rubber rec- 90 tangular in cross section having a wire or cord 6 embedded in its center. This strip of rubber with the wire is then wound on a suitable form to obtain the shape as shown in Figs. 1 and 2. While still held in the 95 form or in a suitable mold, the rubber is vulcanized so as to form a permanent ring.

When the container shown in Fig. 1 is to be used, the jar is filled with the food products to be preserved, these being preferably 100 put in hot in the usual way. The sealing ring 5 is loosely inserted in the cover, which is cold and easily handled, and then the cover, with the sealing ring, is pushed into place on the conical part of the jar. Preferably a weight is added to the top of the jar or the jar is turned upside down to bring the weight thereof on the cover so as to automatically hold the cover and ring in place until the contents has cooled. After 110 the cooling of the contents, the partial vacuum formed in the jar will prevent the re-

moval of the cover. As shown, the cover is preferably provided with an annular rib around its periphery for the reception of a weight or to serve as a base when the jar is 5 inverted.

When the contents of the jar is to be used, the jar can be easily opened by simply catching hold of the projecting end 7 of the tension member of the ring. By pulling down- 10 ward on this tension member the ring can be progressively unwound and pulled out, its complete destruction as a ring being thus effected. It will be noted that successive annular portions of the ring are destroyed, 15 and preferably removed, successively but that the ring is not bodily withdrawn as a whole.

It will be observed that the glass parts of the container are very simple and present 20 no irregular grooves and projections difficult to clean and easily broken.

It will be understood that containers embodying my invention are adapted to be used not only for domestic purposes in the pre- 25 serving of fruits, etc., but also for factory made and packed products, such as canned vegetables, preserved meats, lard, butter, etc. The glass parts of the jar are capable of being re-used and can be either returned to 30 the factory or can be retained for domestic purposes.

In Figs. 3 and 4 I have shown another embodiment of the invention. The jar 1^a can be the same as or similar to the Mason 35 jars in common use. The cover 3^a can be the usual metal cover used with the Mason jars. The sealing ring 5^a is, in this case, flat instead of conical, but can otherwise be similar to the arrangement already de- 40 scribed.

In using the container as shown in Fig. 3, the jar is filled in the usual way, the ring 5^a is put in place and the cover is screwed down. When the jar is to be opened, it is 45 only necessary to separate the loose end of the wire embedded in the ring and to unwind the ring from beneath the cover. There is no necessity for first turning the cover thus avoiding all the difficulty at- 50 tended with the attempt to do so.

In Fig. 5 I have shown a construction similar to that in Figs. 1 and 2 in that a glass cover is provided. The jar 1^b and the cover 3^b are provided respectively with internal threads 2^b and external threads 4^b 55 adapted to be engaged with each other to hold the cover in place. Between the cover and the top of the jar is a sealing ring 5^b similar to that shown in Fig. 4 and adapted 60 to be similarly used.

In Fig. 6 I have shown another form of container especially adapted for jellies and similar products. The jar 1^c is cup-like in form and the cover 3^c is a metal disk, preferably having its central part depressed to

leave a peripheral flange adapted to lie above the jar. Between this flange and the top surface of the jar wall is a ring 5^c similar to the ring 5^a. The jar is filled in the usual way and when it is to be opened, the 70 ring 5^c is unwound and destroyed in the way already described.

In Figs. 7 and 8 I have shown a sealing ring 5^d in the form of a spirally wound 75 braided cord 6^d which is impregnated with a rubber compound and molded into the form of a ring after which the rubber is cured. It will be observed that in this case the cord 6^d constitutes a tension means 80 spirally embedded in the ring. This ring can be either conical or flat as required, and can be used in the way already described, being unwound by pulling on the end 7^d.

In Figs. 9 and 10 I have shown still another form of ring 5^e, this construction being similar to that shown in Figs. 7 and 8. A braided cord 6^e is provided which is wound in the form of a ring and sewed in place by transverse stitches 8 and the entire ring is impregnated with paraffin or other 90 similar compound. The stitches 8 are relatively weak so that when the ring is to be removed from the jar by unwinding, the 95 stitches can be easily broken.

In Fig. 11 I have shown a ring 5^f having 95 its tension means in the form of a braided or knitted fabric so formed that it can be easily unraveled by pulling on the loose end at 7^f. The fabric is impregnated with paraffin or other similar compound and can be 100 used as before described.

What I claim is:—

1. A container comprising a jar, a cover for the jar, and a sealing ring between the cover and the jar having a tension means 105 embedded therein and adapted to be withdrawn to progressively destroy and remove successive annular portions of the ring while the cover is in place.

2. A container comprising a jar, a cover 110 for the jar, and a sealing ring between the cover and the jar having a tension means spirally embedded therein and adapted to be unwound to progressively destroy the ring while the cover is in place.

3. A container comprising a jar, a cover for the jar, and a sealing ring between the cover and the jar having a tension means spirally embedded therein and adapted to be unwound to progressively destroy and remove the ring while the cover is in place. 115

4. A container comprising a jar, a cover for the jar, and a sealing ring between the cover and the jar having a wire spirally embedded therein and adapted to be unwound to progressively destroy the ring while the cover is in place. 120

5. A container comprising a jar having a conical top, a cover for the jar having a conical part adapted to match the conical 125 130

part of the jar, and a conical sealing ring between the cover and the jar having a tension means embedded therein and adapted to be withdrawn to progressively destroy

5 successive annular portions of the ring while the cover is in place.

6. A container comprising a jar having an external conical surface at its top, a cover for the jar having an internal conical surface 10 adapted to match the conical surface of the jar, and a conical sealing ring between the cover and the jar having a tension means embedded therein and adapted to be withdrawn to progressively destroy successive 15 annular portions of the ring while the cover is in place.

7. As an article of manufacture, a sealing ring comprising a plastic substance and a tension means embedded therein and adapted 20 to be withdrawn to progressively destroy the ring.

8. As an article of manufacture, a sealing ring comprising a plastic substance and a wire embedded therein and adapted to be 25 withdrawn to progressively destroy the ring.

9. As an article of manufacture, a sealing

ring comprising a plastic substance and a spirally arranged tension means embedded therein and adapted to be unwound to progressively destroy the ring. 30

10. As an article of manufacture, a sealing ring comprising a plastic substance and a spirally arranged tension means embedded therein and adapted to be unwound to progressively destroy the ring, the said plastic 35 substance adhering to the tension means as it is unwound.

11. A container comprising a jar having a conical top, a cover for the jar having a conical part adapted to match the conical 40 part of the jar, and a conical sealing ring between the cover and the jar having a tension means spirally embedded therein and adapted to be withdrawn to progressively 45 destroy the ring while the cover is in place.

In testimony whereof, I affix my signature, in presence of two witnesses.

ROBERT J. KRAUSE.
